CLAIM

The ornamental design for a bookmark, as shown and described.

DESCRIPTION

FIG. 1 is a front perspective of my new bookmark; the shading employed in the drawings is understood to represent fabric and is understood to be repeated uniformly throughout the area on which it is applied.

FIG. 2 is a front elevation;

FIG. 3 is a rear elevation;

FIG. 4 is a left side elevation;

FIG. 5 is a right side elevation;

FIG. 6 is a top plan view; and,

FIG. 7 is a bottom plan view.
